CLEANER FOR SPIKED SHOES

Thurl E. Dobbins, 2635 California St.,
Huntington Park, Calif.

Filed May 16, 1960, Ser. No. 60,603

Term of patent 7 years

(Cl. D9—2)

Fig. 1

Fig. 2

Fig. 1 is a perspective view of a cleaner for spiked shoes, showing my new design.

Fig. 2 is an end elevational view drawn to a smaller scale.

The opposite side and end are the same as the side and end that are shown.

I claim:

The ornamental design for a cleaner for spiked shoes, substantially as shown and described.
